UNITED STATES PATENT OFFICE.

FRANK K. LOMBARDY, OF SAN DIEGO, CALIFORNIA.

MECHANICAL TOY.

1,167,575.

Specification of Letters Patent.

Patented Jan. 11, 1916.

Application filed October 5, 1914. Serial No. 865,015.

To all whom it may concern:

Be it known that I, FRANK K. LOMBARDY, a citizen of the United States, and a resident of San Diego, in the county of San Diego 5 and State of California, have invented certain new and useful Improvements in Mechanical Toys, of which the following is a specification.

My invention relates to that class of mechanical toys which are mounted on wheels adapted to be drawn either forward or backward along the floor or ground and the traction of said wheels put in motion parts or all of certain figures mounted in connection 15 therewith.

The objects of my invention are, first, to provide a device of this class in which a plurality of figures may be mounted in connection therewith each of which is provided 20 with a different movement if desired, second, to provide a device of this class which is very simple and economical of construction, durable, easily operated and does not readily get out of order, third, to provide a device of this class which may be made to 25 operate from one to a dozen or more of figures without in any way changing the construction or operation thereof and, fourth, to provide such a device in which any or all 30 of the parts, if broken or lost, may be readily replaced with a minimum of expenditure.

With these and other objects in view as will appear hereinafter my invention consists of certain novel features of construction, combination and arrangement of parts 35 as will be hereinafter described in detail and particularly set forth in the appended claims reference being had to the accompanying drawings and to the characters of reference 40 thereon which form a part of this specification, in which:

Figure 1 is a longitudinal, sectional view of my toy complete and Fig. 2 is a top or plan view thereof.

Similar characters of reference refer to 45 similar parts throughout the several views.

The casing 1, wheels 2, crank shaft 3, wheel 4, arm 5, tongue 6, figures 7, 8, 9 and 10, and cord 11, constitute the principal 50 parts of my mechanical toy.

It will be here noted that I have shown only four figures, it being apparent from the operation of these four figures that any number desired may be operated in the same 55 manner.

The casing 1 is a rectangularly shaped

box on the bottom surface of which is secured a cover 1^a. This casing is provided in its top surface with a round hole 1^b, adapted for the manipulation of the cord 11 therethrough. In the cover 1^a is provided a round hole 1^c adapted for the projection of the wheel 4 therethrough and to turn in any directions therein. This cover is also provided with two slots 1^d adapted to allow the 60 wheels 2 to protrude therethrough and rest on the floor or ground beneath. The rear end of the casing is mounted on the extended ends of the crank shaft 3, which extends through the sides of said casing forming a bearing upon which it rests on said 65 crank shaft. In the front end of this casing 1 is provided a horizontal lug 1^e extending inwardly, in which is pivotally mounted the bifurcated support 4^a which is supported on 70 the axle of the wheel 4 and which is provided with a shoulder upon which the lug 1^e rests. Upon this pivotal mounting is secured the arm 5 at its top end which extends forward through a slot 1^f in the casing 75 immediately above the lug 1^e and to which is pivoted on a horizontal axis the tongue 6. It will be here noted that the tongue may be dispensed with and a string or cord used in 80 its place if desired.

Mounted on the crank shaft 3 is a ring 3^a provided with a hook to which is attached the cord 11 which extends out through the hole 1^b. In the top of the casing 1 adjacent to this hole 1^b there is attached to the 85 cord 11 a plurality of cords, one or more for each figure as desired to operate. In the drawing as illustrated by the figure 7 the arms 7^a are pivoted on each side of the figure on a vertical axis and the cord 11^a extends 90 upwardly and is made with two branches, one extending to each arm of the figure and just above the point where they divide they pass through a hole 7^b of the figure so that when the cord 11^a is tightened the arms are 95 thrown apart at their outward extended ends and when the cord is released they immediately swing together at their outward extended ends by reason of the elastic piece 7^c, the figure 7 representing a person playing 100 cymbals. All of the arms of the different figures are operated in the same manner and by means of the same devices and construction, the only difference being in the manner in which the arms of the figures are 105 mounted as to whether they are on a vertical axis or a horizontal axis or otherwise, and

they operate in accordance with their mounting.

Though I have shown and described a particular construction, combination and arrangement of parts I do not wish to be limited to this particular construction, combination and arrangement but desire to include in the purview of my invention the construction, combination and arrangement substantially as set forth in the appended claims.

It is obvious that with this construction, there is provided a mechanical toy in which the arms of the figure mounted thereon may be made to operate horizontally or vertically or both or intermediate between the vertical and horizontal; that with the movement of the toy along the ground the traction of the wheels 2 will revolve the crank shaft 3 which will cause an alternate tightening and loosening of the cord 11 which in turn will operate the arms of the figures mounted thereon; that this device is simple and economical of construction, durable and the parts may be inexpensively replaced or the figures may be readily removed and the device used as a toy wagon.

Having thus described my invention what I claim as new and desire to secure by Letters Patent is:

1. In a mechanical toy, the combination of a casing, wheels upon which said casing is mounted, a crank shaft rigidly secured to a portion of said wheels, a plurality of figures mounted on said casing, some pro-

vided with arms mounted to rotate about a vertical axis and some provided with arms mounted to rotate about a horizontal axis, means in connection with said arms mounted to rotate about a vertical axis, tending to hold them together at their extended ends and a cord provided with branches connecting said crank shaft with the arms of said figures, whereby, with the movement of said crank shaft, said arms are moved upon their mountings.

2. In a mechanical toy, the combination of a frame or casing, wheels upon which said frame or casing is mounted, a crank shaft rigidly secured to said wheels, a cord engaging with said crank shaft whereby it may be alternately tightened or loosened with the revolution of the wheels, a plurality of figures each provided with arms mounted to rotate about a vertical axis to which branches of cord are attached and means in connection with said arms mounted on a vertical axis for normally holding them together at their extended ends whereby said arms are made to move upon their pivotal mountings with the tightening and loosening of said cords.

In witness whereof, I have hereunto subscribed my name in the presence of two subscribing witnesses.

FRANK K. LOMBARDY.
